UNITED STATES PATENT OFFICE.

JOHN C. KITTON, OF CHICAGO, ILLINOIS.

REFRIGERATORY APPARATUS.

1,250,898.

Specification of Letters Patent. Patented Dec. 18, 1917.

Application filed September 11, 1916. Serial No. 119,342.

To all whom it may concern:

Be it known that I, JOHN C. KITTON, a citizen of the United States of America, residing at Chicago, in the county of Cook and State of Illinois, have invented certain new and useful Improvements in Refrigeratory Apparatus, of which the following is a specification, reference being had therein to the accompanying drawings.

- 10 This invention relates to a refrigeratory apparatus and my invention is characterized by a novel compressor, a condenser, a heat absorbing device, pressure regulating valves, and cooling and lubricating systems, all of which are compactly arranged to insure a high degree of efficiency in gasifying ammonia and similar fluids and restoring the ammonia gas to its original condition by condensing.
- 20 The condenser is of novel design including inner and outer communicating and circumferentially disposed conduits providing a sinuous or tortuous passage for ammonia gas and the arrangement of the conduits is such that the compressor proper is disposed centrally of all of the condenser conduits with a water jacket surrounding the same. This arrangement provides a compact structure and accessibility.
- 30 The heat absorbing device affords a lengthy sinuous or tortuous passage for ammonia or a similar fluid and provides a large area exposed to the action of a cooling agent so that ammonia or a similar fluid passing through the device may be expeditiously and economically gasified.

The pressure regulating valves are of the diaphragm type and are an important adjunct of the entire apparatus by automatically controlling the pressure of ammonia gas to the compressor. By regulating the supply of ammonia gas to the compressor and automatically controlling the same, less power is required when starting the compressor, as ammonia gas is prevented from accumulating in the compressor when there is a cessation in the operation of the same.

The cooling system of the apparatus includes a water jacket for the bearing of the main driven shaft of the apparatus and this bearing water jacket is in communication with the water jacket of the condenser so that a cooling agent, as water, may be circulated around desired parts. The lubricating system includes lubricant receptacles or wells containing pumps and the lubricant

is automatically circulated and carried to the principal bearings of the apparatus, and allowed to drop into its former receptacle, thus avoiding churning of oil and preventing vapor of oil going over with ammonia gas.

The invention is further characterized by an apparatus wherein the parts are constructed with a view of reducing the cost of manufacture and at the same time retain those features by which durability, simplicity of construction and ease of assembling are secured, and with such ends in view my invention resides in the novel construction, combination and arrangement of parts to be hereinafter specifically described and then claimed.

Reference will now be had to the drawings, wherein—

Figure 1 is a vertical longitudinal sectional view of the refrigeratory apparatus, somewhat diagrammatically illustrated;

Fig. 2 is a vertical sectional view of the compressor and condenser of the apparatus;

Fig. 3 is a horizontal sectional view taken on the line III—III of Fig. 2;

Fig. 4 is a horizontal sectional view of the main bearing of the apparatus;

Fig. 5 is an elevation of the apparatus, partly in section, showing the preferred arrangement of devices;

Fig. 6 is a similar view taken on the line VI—VI of Fig. 4;

Fig. 7 is a plan of the compressor, partly broken away and partly in section, and

Fig. 8 is an enlarged sectional view taken on the line VIII—VIII of Fig. 7.

In describing my invention by aid of the views above referred to, I desire to point out that the same are intended as merely illustrative as an example whereby my invention may be put to practice, and I do not care to confine myself to the precise construction and arrangement of parts shown. The following description is therefore to be broadly construed as including substitute constructions and arrangements of parts which are the obvious equivalent of those to be hereinafter referred to.

In the drawings, 1 denotes a foundation or bed plate for a longitudinal bearing 2 which is cored out or bored to provide an ammonia chamber 3, a water chamber or jacket 4, and a lubricant and hydraulic chamber 5, said lubricant chamber being concentric of the water chamber or jacket 4.

One end of the lubricant chamber 5 terminates at a bearing 6 for a driven shaft 7, said shaft being journaled in a stuffing box 8 closing the opposite end of the lubricant 5 and hydraulic chamber 5.

9 denotes a transmission housing suitably connected to that end of the bearing 2 containing the stuffing box 8 and said transmission housing is preferably made in two 10 parts suitably connected together, as at 10, so that easy access may be had to the interior of the housing. The driven shaft 7 extends through the housing 9 and is journaled in a stuffing box 11 carried thereby. 15 On the shaft 7, within the housing 9, is a large gear wheel 12 meshing with a small gear wheel 13 mounted on a motor shaft 14. The motor shaft 14 is journaled in a stuffing box 15 forming part of the transmission 20 casing 9 and said shaft is part of an electric motor 16 that can be advantageously mounted on the top of the bearing 2.

17 denotes a crank case mounted upon the bed plate or foundation 1, against the end 25 of the bearing 2, and said crank case incloses the crank portion 18 of the driven shaft 7 and provides a lubricant reservoir 19. The crank case 17 has a detachable bearing 17* for the end of the driven shaft 7 and this bearing is supplied with a lubricant, as will hereinafter appear.

The upper end of the crank case 17 has an opening 20 and extending therein is the lower end 21 of a compressor cylinder 22. 35 The lower end 21 of the compressor cylinder has an annular groove cooperating with a similar groove in the upper end of the crank case in providing a channel 23 and this channel is in communication with a 40 plurality of upwardly directed angularly disposed ports 24, said ports communicating with the bore 25 of the cylinder 22.

26 denotes a piston body slideable in the lower end of the cylinder bore 25 and said 45 piston body is connected by a connecting rod 27 to the crank portion 18 of the driven shaft 7. The inner end of the piston body 26 is provided with a rod 28 having a valve head 29. Slidable upon the rod 28 is a piston 50 ton 30 having the usual packing rings insuring a non-leakable connection between the walls of the piston and the walls of the cylinder bore 25. The piston 30 serves as a valve seat member for the valve head 29, 55 said piston inclosing the valve head 29 and being hollowed out to provide clearance therefor. Encircling the rod 28 between the valve head 29 and the piston 30 is a coiled compression spring 31 holding the piston 60 or valve seat member normally seated upon the valve head 29. The piston 30 has longitudinal ports 32, normally communicating with the lower end of the cylinder bore 25 and adapted for establishing communication 65 between the ports 24 and the upper end

of the cylinder bore 25 when the valve head 29 reedes from its seat in the piston 30.

33 denotes a check valve body mounted upon the upper end of the compressor cylinder 22 and having a valve seat portion 70 34 at the upper end of the cylinder bore 25. The check valve body 33 has a ported guide 35 for a spring pressed normally closed check valve 36 cooperating with the valve seat portion 34 of the check valve body 33 75 in normally closing the upper end of the cylinder bore 25.

37 denotes a circular condenser head mounted on the check valve body 33 and said head has circumferentially disposed 80 stepped connections 38 for inner conduits 39 and outer conduits 40, the latter inclosing the former and having the lower ends thereof closed. These inner and outer conduits constitute condenser chambers arranged in 85 proximity to the compressor cylinder 22 and circumferentially thereof, such arrangement insuring compactness.

41 denotes a cap mounted on the condenser head 37. The cap 41 has a radially 90 disposed passage 42 communicating with an opening 43 centrally of the condenser head 37 and the opening 23 permits of the passage 42 communicating with the upper end 95 of the cylinder bore 25, when the check valve 36 is unseated. The passage 42 communicates with one of the inner conduits 39 and the remaining inner conduits 39 are each connected by short recesses 44 and ports 45 in the condenser head 37 to the upper 100 ends of the outer conduits 40, and in consequence of this arrangement ammonia gas passing through the passage 42 is admitted to an inner conduit 39 to pass throughout the length thereof into the bottom of an 105 outer conduit 40, ascend in said outer conduit to pass through a port 45 into the upper end of another inner conduit, down the conduit and up an outer conduit and so on, until the ammonia gas eventually passes 110 out of the upper end of an outer conduit 39 into ports generally designated 45. By reference to Fig. 1, it will be noted that the ports generally designated 45 are formed in the condenser head 37, the walls of the compressor cylinder 22, walls of the crank case 115 17, and walls of the bearing 2, said ports opening into the ammonia reservoir 3. It is therefore apparent that the inner and outer conduits 39 and 40 in conjunction with 120 the condenser head 37 and the cap 41 thereof, provide a sinuous or tortuous passage for ammonia gas from the compressor cylinder 22 and that before the ammonia gas has traversed the up and down passage of the 125 condenser, that it has been converted into liquid ammonia and finally collected in the ammonia chamber 3.

47 denotes a pipe connecting the bottom 130 of the ammonia chamber 3 with a primary

regulating and controlling valve generally designated 48 and best shown in Fig. 1. The primary regulating valve comprises bodies 49 and 50, the former housing a needle valve 51 controlling admission of liquid ammonia to the body 49. The needle valve 51 is adjusted through the medium of a pivoted bell crank 52, a link 53, and a rod 54, said rod extending into the body 50 where it is connected to a diaphragm 55 within said body. Flexure of the diaphragm 55 is regulated by a set screw 56 and an interposed coiled compression spring, the tension of the spring being regulated by the screw 56. Extending through the screw 56 is an adjustable rod 56^a attached to the upper face of the diaphragm and by adjusting the screw 56 the diaphragm may be flexed upward and held so that the regulating valve may be utilized as a shut-off valve.

58 denotes a pipe communicating with the bottom of the body 49 and said pipe extends through a tank 59 adapted to contain a cooling agent, as brine. The inner end of the pipe 58 is connected to a distributing head 60 within the cooling tank 59. Extending through the head 60 in superposed relation are parallel inner conduits 61 and inclosing said conduits, at opposite sides of the head 60, are longitudinally alining outer conduits 62 and 63. The pipe 58 communicates with the lowermost outer conduit 63 and the inner ends of the outer conduit 62 are connected to the inner ends of the outer conduits 63 by angularly disposed ports in the head 60. The upper-most outer conduit 62 has an outlet through the head 60 to a pipe 65, and it will be noted that the inner and outer conduits 61, 62 and 63 in conjunction with the distributing head 60, provide a sinuous or tortuous passage for ammonia through the cooling tank 59. Thus the outer conduits 62 and 63 present large areas to the cooling action of the brine agent within the tank 59, and the ammonia is thoroughly gasified before reaching the outlet pipe 65.

66 denotes the body of a dual regulating and controlling valve and said body is connected to the pipe 65 to receive ammonia gas therefrom. In the valve body 66 are needle valves 67 and 68, the former controlling a large port and the latter a small port, as best shown in Fig. 1. These needle valves are regulated through the medium of pivoted bell cranks 69, diaphragm rods 70 and diaphragms 71, the flexure of the latter being furthermore regulated by set screws 72, adjustable rods 72^a, and coiled compression springs 73. The adjustable rods 72^a permit of the regulating valve being used as shut-off valves, similar to the valve 48. The admission of ammonia gas to the valve body 66 is controlled by the needle valves 67 and 68 and said valve body has a passage

74 connected by a pipe 75 to the diaphragm body 50 of the primary regulating valve 48.

76 denotes a pipe connecting the passage 74 of the valve body 66 to a port 78 in the wall of the crank case 17, this last mentioned port communicating with channel 23 in the lower end of the compressor cylinder 22.

Before considering the cooling and lubricating systems of the apparatus, I will describe the converting of liquid ammonia into ammonia gas and vice versa.

Assuming that the compressor is placed in operation by starting the motor 16, an upstroke of the piston or valve seat member 30, which is raised by the rod 28 and the valve head 29 pulls ammonia gas through the lower end of the bore 25 of the compressor cylinder 22. The downstroke of the piston body 26 unseats the piston 30 relative to the valve head 29, allowing the ammonia gas to pass through the piston 30 into the upper end of the cylinder 25, and then upon another upstroke of the piston body 26, the ammonia gas is compressed, the check valve 36 unseated, and the ammonia gas forced into the condenser inner and outer conduits 29 and 40. The ammonia gas, by reason of these condenser conduits being cooled as will hereinafter appear, is eventually discharged from the condenser in liquid form and flows through the ports 45 to the ammonia chamber 3. From the ammonia chamber 3, the ammonia flows by gravity to the primary regulating valve 48, and assuming that the needle valve 51 allows the liquid ammonia to flow through the body 49 into the pipe 58, the liquid ammonia is gasified by absorbing heat from the contents of the tank 59 and is emitted from the heat absorbing device as ammonia gas. Passing through the pipe 65 the ammonia gas enters the dual regulating valve 66 and further assuming that conditions are normal the ammonia gas is drawn through the pipe 76, and port 78 into the compressor. This operation is continuous as long as conditions are normal. If the compressor is to be operated under fifteen pounds suction pressure, as an instance, then the primary regulation valve 48 is adjusted whereby fifteen pounds suction pressure for operating the compressor will, through the medium of the diaphragm 55 adjust the needle valve 51 so that a desired or predetermined quantity of liquid ammonia will be admitted to the heat absorbing device to be gasified thereby. In consequence of this arrangement, the primary regulating valve 48 will insure a proper supply of gasified ammonia to the compressor under normal conditions.

As illustrating the necessity of using the dual valve 66, I will assume that the apparatus has been in operation for some time and is then shut down. As there will be liquid ammonia in the heat absorbing de-

vice, the ammonia will be gasified and held from entering the compressor by reason of the needle valves 67 and 68. If it were not for these needle valves, which are automatically adjusted by excessive ammonia gas pressure, the excessive pressure of ammonia gas would pass into the compressor thereby requiring considerable power, undoubtedly greater than that of the motor 16, to start the compressor. It is therefore the purpose of the dual valve 66 to prevent an excessive pressure of ammonia gas from entering the compressor. Assuming that the diaphragm of the needle valve 67 is regulated for twenty pounds pressure and the diaphragm of the needle valve 68 for twenty-five pounds pressure, then on starting the compressor, the needle valve 67 is first opened, then the needle valve 68, and as the excessive pressure is gradually reduced or assumed normal, the diaphragm 55 of the primary regulating valve eventually opens the needle valve 51, thereby allowing liquid ammonia to flow to the heat absorbing device for gasifying purposes. The dual valve 66 therefore performs an important function in connection with the apparatus by preventing an excessive pressure or accumulation of gasified ammonia from retarding the usual starting operation of the compressor, otherwise, the compressor may be rendered inoperative unless provision was made for using greater power for starting the apparatus than used under normal operations.

Considering the cooling system in connection with the bearing 2 and the condenser, water or a similar cooling agent is admitted through a pipe 83* and a port 83 into the top of a chamber or jacket 40 formed by placing a cover 82 upon the upper end of the crank case 17, to inclose the condenser conduits. The water jacket or chamber surrounding the condenser conduits has an outlet through an overflow pipe 45 81 and ports 80 and 79 into the chamber 4 and from said chamber through an outlet port 79*, consequently water or a similar agent can be circulated around the bearing 2 of the compressor, keeping it at a normal 50 temperature.

The lubricating system includes two pumps 84 and 85 the former being located in the transmission casing 9 and operated from the driven shaft 7. The pump 84 55 raises what lubricant that may accumulate within the transmission casing 9 to the lubricant chamber 5 around the driven shaft 7. This is accomplished by a pipe 86 connecting the pump with a port 87 of the bearing leading to the chamber 5. The pipe 86 has a check valve 88 and a release valve 89, both of these valves being of a conventional form. Within the lubricant chamber 5 is an apertured sleeve 90 and this 60 sleeve retains suitable packing 91 at the ends

of the lubricant chamber 5 and contiguous to the bearing 6 and the stuffing box 8. The pump 84 raises what oil is necessary to raise the pressure in chamber 5 say to fifty pounds—the release valve being set at that 70 pressure or any pressure to overcome the effects of pressure in the crank case 17, thereby insuring against stuffing box leakage and creating an automatic packed stuffing box.

The pump 85 is located within the crank case 17 and has a depending pipe 92 extending into the lubricant well or reservoir 19. Another pipe 93 leads from the pump 85 to the bearing 17* of the crank case 17, 80 and then by ports 94 to other bearings of said crank case, where it drops back into receptacle 19 and prevents the crank from threshing the oil into vapor to be carried over with the ammonia gas.

As heretofore mentioned, Fig. 1 is more or less diagrammatic, and as an instance of a preferred arrangement, the compressor and condenser have been shown in Fig. 5: as being mounted directly above the heat 90 absorbing device, with the primary and dual regulating valves in the brine of the tank 59. This arrangement eliminates valves, elbows, pipes and exposed fittings, as all parts containing ammonia gas are under water 95 or brine, thus providing a fool proof and safe outfit that can be advantageously used for household purposes.

What I claim is:—

1. In a refrigeratory apparatus, a bearing 100 provided with a water jacket and water ports extending to the bottom and end thereof, a compressor having a ported crank case abutting an end of said bearing, a condenser surrounding said compressor adapted to receive gas therefrom, a water jacket inclosing said condenser adapted to receive water to overflow into the ported crank case of said compressor and enter the jacket of said bearing; an ammonia chamber in said bearing in communication with said condenser and adapted to receive ammonia through the ported bearing and crank case of said compressor, a primary regulating valve adapted to receive ammonia from 110 said chamber, and a heat absorbing device 115 in communication with said valve and said compressor and adapted to supply ammonia gas to said compressor.

2. In a refrigeratory apparatus, a bearing 120 having a water jacket, an ammonia chamber, said bearing having ammonia and water ports, a driven shaft extending through said bearing, a compressor at one end of said bearing operated at one end of said shaft 125 and provided with ports registering with the ports of said bearing, a condenser surrounding said compressor and adapted to receive gas therefrom, a water jacket inclosing said compressor, said compressor having 130

ing ports registering with ports of said bearing to communicate with the water jacket of said bearing, a primary regulating valve adapted to receive ammonia from said 5 chamber, a heat absorbing device in communication with said valve, and a dual regulating valve in communication with said primary valve and said heat absorbing device, and said compressor adapted for regulating the pressure of gas from said heat absorbing device to said compressor.

3. In a refrigeratory apparatus, the combination with a compressor, a condenser, and a heat absorbing device adapted for supplying ammonia gas to said compressor and receiving liquid ammonia from said condenser, of a primary diaphragm actuated regulating valve normally in communica- 15

tion with said heat absorbing device and adapted to be operated by a fluctuation in 20 the pressure of gas in the heat absorbing device and adapted to control the supply of liquid ammonia to said heat absorbing device, and a dual pressure actuated regulating valve interposed between said primary 25 valve and said heat absorbing device adapted to be successively actuated by excessive pressures of gas from said heat absorbing device.

In testimony whereof I affix my signature 30 in presence of two witnesses.

JOHN C. KITTON.
